CLAIM

The ornamental design for a rice cooker, as shown and described.

DESCRIPTION

FIG. 1 is a view of a rice cooker in accordance with the present disclosure from the front;

FIG. 2 is a view of the rice cooker shown in FIG. 1 from the rear;

FIG. 3 is a view of the rice cooker shown in FIG. 1 from the left;

FIG. 4 is a view of the rice cooker shown in FIG. 1 from the right;

FIG. 5 is a view of the rice cooker shown in FIG. 1 from the top;

FIG. 6 is a view of the rice cooker shown in FIG. 1 from the bottom; and,

FIG. 7 is a perspective view of the rice cooker shown in FIG. 1.

1 Claim, 7 Drawing Sheets
